LAPPING MACHINE

Nathan A. Randall, West Allis, Wis., assignor to Allis-Chalmers Manufacturing Company, Milwaukee, Wis.
Filed Oct. 23, 1961, Ser. No. 145,714
3 Claims. (Cl. 340—265)

This invention pertains to a machine for lapping the bearing surfaces of mating elements. The invention is more particularly concerned with such a machine wherein a warning device is provided which indicates when the surfaces being lapped are likely to seize.

Although it is not intended to limit the invention to a machine for lapping the blade roots of a steam turbine, the invention will be described in relation to the lapping of turbine blades since this is one particular area where the machine has solved a long existing problem.

In impulse steam turbines the blade roots are quite frequently formed in the shape of a fir tree having a number of radially spaced tangs simulating the branches of the tree. These tangs fit into radially spaced grooves provided in the turbine spindle. The tangs and grooves present axially extending complementary bearing surfaces. In this manner, a very solid connection is provided between the turbine blades and the turbine spindle. As the spindle rotates, the blades have a tendency, due to centrifugal force, to be flung radially outward from the spindle. This causes the radially outer surfaces of the blade tangs to bear on the radially inner surfaces of the spindle grooves. If the mating surfaces of these grooves and tangs are not accurately finished, the large centrifugal force will not be equally distributed between all of the grooves and tangs. If there should be a concentration of this centrifugal force on one or two blade tangs, it is quite possible that the blade or groove will crack resulting in a failure of the turbine blade whereby it may be severed from the turbine spindle and be flung outward doing considerable damage to the turbine and surrounding area. Such a failure is not only costly but is extremely dangerous due to the high rotational speed of the turbine blades and the resultant large centrifugal force involved.

It would, therefore, be desirable to lap the blade root tangs to the spindle grooves so that the load is equally divided between all of the tangs and grooves. However, lapping turbine blades has been extremely difficult prior to applicant's invention because of the close clearances between the mating surfaces of the blade and spindle required by the lapping process. During the lapping process, if there is actual metal to metal contact between the blade and spindle, the two parts may weld together in local areas due to heat caused by rubbing friction. This may so damage the mating surfaces that the blades in some instances must be scrapped. It is, therefore, desirable to provide a means of determining when metal to metal contact is about to occur slightly before the contact actually takes place or immediately upon contact so that the lapping process can be stopped before the surfaces are damaged.

It is, therefore, a general object of the subject invention to provide a lapping machine with a warning device which indicates when metal to metal contact between the mating surfaces is about to take place.

A further object of the subject invention is to provide a lapping machine of the hereinbefore described type wherein an electric circuit is provided in series with the elements to be lapped which circuit includes an indicating device which indicates when the mating surfaces are about to come into contact with one another.

An additional object of the subject invention is to provide a lapping machine of the hereinbefore described type wherein the lapping compound acts as a resistance in the electrical circuit thereby increasing and decreasing the

intensity of the signal as the distance between the mating surfaces is decreased and increased, respectively.

A further object of the subject invention is to provide a lapping machine of the hereinbefore described type wherein the indicating device is a common light bulb which glows brighter as the mating surfaces approach one another and the amount of lapping compound between these surfaces is decreased.

An additional object of the subject invention is to provide a lapping machine of the hereinbefore described type wherein an additional light bulb is connected in the electrical circuit in a manner to glow brightly at all times in order to provide a comparison with the light bulb connected in series with the mating surfaces of the elements to be lapped.

These and other objects of the subject invention will become more fully apparent as the following description is read in light of the attached drawing wherein:

FIG. 1 is a side elevation of a machine constructed in accordance with the invention;

FIG. 2 is an end elevation of FIG. 1; and

FIG. 3 is an enlarged view of the mating surfaces of a turbine blade and spindle shown for purposes of illustration.

For purposes of illustration, the invention is shown in the drawing in condition for performing a lapping operation on the bearing surfaces of a turbine spindle and turbine blades. Referring to the drawing, a turbine spindle 1 is supported above the machine in any conventional manner such as by supports 2. The turbine spindle is provided with a series of axially extended grooves 3 in which is received a turbine blade root 4. As herein shown in FIG. 2 for purposes of illustration, the turbine blades 6 are fastened together and form pairs which are lapped at the same time. Each blade root 4 is provided with a series of axial extending tangs 7 grouped so that the blade root resembles a fir tree.

Referring particularly to FIG. 2, the turbine blades 6 are rigidly connected to a table 8. This connection may be provided in any conventional manner and is herein shown for purposes of illustration as including wedges 9 having their lower flat surfaces resting on the top of table 8 and having their upper inclined surfaces tangent to the convex outer surface arc of the turbine blades. Clamps 11 fit over an integral blade shroud 12 on the outer end of the turbine blades and are rigidly connected to the top of table 8 by means of bolts 13. In this manner the turbine blades 6 are rigidly connected to the top of table 8.

The table 8 is provided with a subframe or undercarriage 14 having a longitudinally extending angled groove 16 on the under side thereof. A rail member 17 having a complimentary angled flange 18 fits into the angled groove 16 of the undercarriage of the table 8. In this manner the table and undercarriage may be moved in a longitudinal direction on the flange 18 and maintain a very accurate transverse position relative to the spindle 1.

During the lapping process it is necessary to raise or lower the blades 6 relative to the turbine spindle and any conventional means may be provided for this purpose. As herein shown for purposes of illustration, two complimentary angled blocks 19 and 21 are provided for this purpose. These blocks have identically angled mating surfaces to permit raising and lowering of the table 8 without changing the angular position of the table relative to the turbine spindle. The lower block 21 is rigidly connected to a bed plate 22.

Any conventional means may be provided for moving the block 19 and as herein shown for purposes of illustration, two screws 22 and 23 are provided in internally threaded stanchions 24 and 26. Lock nuts 27 and 28 are provided to hold the block 19 in its adjusted position.

Any conventional means may be provided to cause the table 8 to oscillate relative to the turbine spindle 1. For purposes of illustration, a conventional two way hydraulic cylinder 29 is shown attached to a support 31 by means of a pivot pin 32. A piston rod 33 connected to the piston of cylinder 29 is pivotally connected to a flange 34 provided on one end of the table 8.

An electrical indicating circuit 36 is connected in series with the turbine spindle 1 and turbine blades 6. Any electrically responsive indicating means such as a conventional light bulb 37 may be provided in this circuit. A conventional battery 38 connected in the indicating circuit 36 provides the current to light the bulb 37 when the surfaces between the blade tangs and turbine spindle grooves are in contact.

A comparison circuit 39 is also provided. This circuit 39 consists of a light bulb 41 identical to the light bulb 37 which is connected by the wire 42 to one side of the battery 38. The other side of the battery 38 is connected by the wire 43 to the light bulb 41 and this wire 43 has a conventional on and off switch 44 provided therein. It should be noted that both light bulbs 37 and 41 are identical and that both receive current from the same battery so that both will glow at the same intensity when there is metal to metal contact between the spindle 1 and blades 6.

In order to lap the turbine blade tangs 7 to the spindle grooves 3, the turbine spindle 1 is first supported in any conventional manner so that its longitudinal axis is parallel to the bed plate 22. The turbine blades 6 are then slipped into the spindle grooves 3 and a wedge (not shown) is driven between the end of the turbine blade roots and into a groove 46 provided in the bottom of the spindle grooves. In this manner the turbine blades 6 are forced radially outward relative to the spindle and the tangs 7 come into contact with the mating or bearing surfaces of the spindle grooves. The table 8 is then raised to a position closely adjacent to the outer ends of the turbine blades and the wedges 9 are tapped between the outer ends of the blades and the table surface. The clamps are then attached to the table top and hold the blades firmly in position on the table. The wedge in groove 46 is then removed. At this point the light bulb 37 will be glowing at its greatest intensity and will be substantially equal to the intensity of the light bulb 41. The table 8 is raised slightly by means of the block 19 and bolt 22 until the light bulb 37 reduces intensity or ceases to glow. When the light bulb 37 ceases to glow or reduces light intensity, the operator is assured that there is no contact between the turbine blades and turbine spindle. The table 8 is then moved by the cylinder 29 so that the blade roots 4 are completely removed from the grooves in the spindle 1. Lapping compound is then applied to the surfaces of the tangs 7 which are to be lapped with the mating surfaces of the spindle grooves. The blade roots are then moved back into the spindle grooves and the lapping process begins. Because of the insertion of the lapping compound between the surfaces of the blade roots and turbine grooves, the light bulb 37 will glow slightly. However, the lapping compound is, in effect, a resistance to the flow of current and, therefore, the light bulb 37 will not glow as brightly as the light bulb 41 and the operator will know that there is no direct metal to metal contact between the blade tangs and the spindle grooves. As the blade roots are moved back and forth over the surfaces of the spindle grooves, the lapping compound grinds the surfaces to a velvet finish. After a predetermined number of passes through the grooves, the blade roots 4 are lowered a predetermined amount which is indicated by a dial 47 having a pointer in contact with the top of the surface of the block 19. The lapping process again is repeated in the new lowered position and the operator again notices the intensity at which the light bulb 37 glows. If the bulb 37 glows at an intensity close to the intensity of the light bulb 41,

the operator is aware that there is about to be surface to surface contact between the surfaces of the blade roots and spindle grooves and, therefore, the lapping process is stopped and the blades are raised slightly until the light bulb 37 glows at an intensity substantially less than the intensity of the light bulb 41.

With this arrangement applicant has provided an inexpensive and simple manner of determining when seizing is about to take place between surfaces that are being lapped. It should be understood that the clearances between surfaces such as that shown for purposes of illustration herein, are so slight that it is impossible to determine when there is actual contact merely by visual inspection. In the past, the operator would not be able to determine exactly when surface to surface contact took place and for this reason seizing was a problem. With the present simple and inexpensive arrangement, the operator knows when metal to metal contact is about to take place and the machine can be readjusted to insure that seizing will not result.

It should also be understood that there are a number of different indicating devices which could be used in place of the light bulbs shown herein. One such device would be an ohmmeter. With an ohmmeter there would be no need for the comparison circuit 39. Through trial and error it could be determined what reading on the ohmmeter would insure that the mating surfaces were at the ideal spacing for lapping. Another reading on the ohmmeter would indicate that the surfaces were too far apart for proper lapping. Another reading would indicate that the surfaces were too close and might actually touch. It can thus be seen that the invention in its broadest light lends itself to many modifications as to the type of indicating means to be used.

Although only one embodiment of the subject invention has been shown, it will be apparent to those skilled in the art that various embodiments are suggested and it is intended to cover all such embodiments coming within the scope of the appended claims.

Having now particularly described and ascertained the nature of my said invention and the manner in which it is to be performed, I declare that what I claim is:

1. A machine for lapping the mating surfaces of elements including the use of a lapping compound comprising: a first support for holding one of said elements; a second support for holding the other of said elements, said supports being positionable to hold said mating surfaces in spaced apart parallel relation to permit insertion of said lapping compound therebetween; first means for moving said elements in a manner to increase and decrease said spacing between said mating surfaces; second means for moving one of said elements relative to the other of said elements, said relative movement being in a plane parallel to the planes of said mating surfaces; electric circuit means connected in series with said elements and including a source of electric energy and a variable indicating means, said variable indicating means being responsive to changes in the resistance of said circuit and the resistance of said circuit being proportional to the amount of said lapping compound between said mating surfaces; and a nonvariable indicating means continuously giving an indication which is identical to the indication given by said variable indicating means when said elements are in physical contact.

2. A machine for lapping the mating surfaces of elements comprising: a first support for holding one of said elements; a second support for holding the other of said elements, said supports being positionable to hold said mating surfaces in spaced apart parallel relation to permit insertion of lapping compounds therebetween; first means for moving said elements in a manner to increase and decrease said spacing between said mating surfaces; second means for moving one of said elements relative to the other of said elements, said relative movement being

in a plane parallel to the planes of said mating surfaces; first electric circuit means connected in series with said elements and including a source of electric energy and a first indicating means, said indicating means being responsive to changes in the resistance of said circuit, and the resistance of said circuit being proportional to the spacing of said mating surfaces; and second circuit means connected in series with said source and including a second indicating means identical to said first indicating means, said second indicating means giving a continuous indication identical to the indication of said first indicating means when the resistance in said first circuit is at a minimum.

3. A machine for lapping the mating surfaces of elements comprising: a first support for holding one of said elements; a second support for holding the other of said elements, said supports being positionable to hold said mating surfaces in spaced apart parallel relation to permit insertion of lapping compound therebetween; first means for moving said elements in a manner to increase and decrease said spacing between said mating surfaces; second means for moving one of said elements relative to the other of said elements, said relative movement being in a plane parallel to the planes of said mating sur-
